PIPE CUTTER

Robert B. Pealer, Garrettsville, Ohio, assignor to
Beaver Pipe Tools, Inc., Warren, Ohio, a cor-
poration of Ohio

Application March 7, 1952, Serial No. 18,812

Term of patent 14 years

(Cl. D54—13)

To all whom it may concern:

Be it known that I, Robert B. Pealer, a citizen of the United States, residing at Garrettsville, county of Portage, State of Ohio, have invented a new, original, and ornamental Design for a Pipe Cutter, of which the following is a specification, reference being had to the accompanying drawings, forming a part hereof.

Fig. 1 is a side view of a pipe cutter, showing my new design; Fig. 2 is an elevational view at right angles to Fig. 2, and Figs. 3 and 4 are sectional views as indicated by the correspondingly numbered lines on Fig. 1.

I claim:

The ornamental design for a pipe cutter, as shown.

ROBERT B. PEALER.
